SEPARATOR FOR EGG YOLK AND WHITES OR SIMILAR ARTICLE

Filed Feb. 15, 1944

Inventor:

Edwin Reynolds

UNITED STATES PATENT OFFICE

138,398

DESIGN FOR A SEPARATOR FOR EGG YOLK AND WHITES OR SIMILAR ARTICLE

Edwin Reynolds, Vineland, N. J.

Application February 15, 1944, Serial No. 112,598

Term of patent 14 years

(Cl. D44—29)

To all whom it may concern:

Be it known that I, Edwin Reynolds, a citizen of the United States, residing at Vineland, in the county of Cumberland and State of New Jersey, have invented a new, original, and ornamental Design for a Separator for Egg Yolk and Whites or Similar Article, of which the following is a specification, reference being had to the accompanying drawing, forming part thereof.

The figure is a perspective view of a separator for egg yolk and whites or similar article, showing my design.

I claim:

The ornamental design for a separator for egg yolk and whites or similar article, substantially as shown.

EDWIN REYNOLDS.
